[57] **CLAIM**

I claim the new, original ornamental design for the jeweled cube pendant for necklace, as shown in the drawings and described in the specification.

DESCRIPTION

FIG. 1 is a top front perspective view with open lid of the jeweled cube pendant for necklace of the present invention; FIG. 2 is a top back perspective view with closed lid showing the hanging ring of the jeweled cube pendant of FIG. 1;

FIG. 3 is a front plan view of the jeweled cube pendant of FIG. 1;

FIG. 4 is a left plan view of the jeweled cube pendant of FIG. 1;

FIG. 5 is a right plan view of the jeweled cube pendant of FIG. 1;

FIG. 6 is a back plan view of the jeweled cube pendant of FIG. 1;

FIG. 7 is a top plan view of the jeweled cube pendant of FIG. 1; and,

FIG. 8 is a bottom plan view of the jeweled cube pendant of FIG. 1.
